UNITED STATES PATENT OFFICE.

JOHN E. OSTLINE, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

MULTIOFFICE TELEPHONE SYSTEM.

Application filed October 18, 1922. Serial No. 595,251.

The present invention relates to multi-office telephone systems in general, but is concerned more particularly with multi-office telephone systems in which there are both 5 manual and automatic offices, and the principal object, briefly stated, is the provision of new and improved circuit arrangements, whereby calls originating in an automatic office and intended for a subscriber whose 10 line terminates in a manual office may be handled in a desirable and efficient manner.

More specifically, the present invention provides a device, which will be termed hereinafter a coder, which is located in an automatic office, and which stores up the impulses representing the various digits in the desired subscriber's number, and which transmits a corresponding series of coded 15 impulses to the manual office when the operator thereat is ready to set up the connection.

In order to give a full understanding of the advantages of such an arrangement, the situation which necessitated the invention 20 will be briefly reviewed. As is well-known, a type of automatic telephone switching equipment which is known as "panel" or "machine switching" equipment has been evolved for multi-office systems. When a 25 step by step automatic office is installed in a multi-office system already containing manual and machine switching offices, it is desired to have all the indicating devices in the manual office the same, regardless of 30 whether the call is coming from a machine switching office or from a step by step automatic office.

In the machine switching system, the subscriber's number is received at the central 35 office upon a device known as a sender, which sender directs the machine switches in accordance with the desired number. When a system is installed in which there are machine switching offices and manual offices, the senders in the machine switching offices 40 are arranged so as to trunk the call through to the desired manual office in the usual manner, and then to send a series of coded impulses to the manual office upon the response of the operator. These coded 45 impulses cause the desired number to be displayed on the operator's set of display or call indicator lamps.

Heretofore, calls from step by step auto-

matic offices to manual call indicator offices 55 have been handled by providing a plurality of register sets in each manual call indicator office, which register sets store up the desired numbers as they come in. The numbers are switched on to the common set of 60 display lamps one at a time, as each preceding call is completed by the operator. Obviously, this system may be used in handling calls, not only from step by step 65 automatic offices, but also from machine switching automatic offices, but an investigation seems to reveal that it is easier and more efficient to arrange the step by step automatic equipment to send out the coded impulses than it is to change the machine 70 switching equipment to operate the call indicators according to the common practice set out above in connection with step by step offices.

Accordingly, a number of coders sufficient 75 to take care of the traffic are provided for each step by step automatic office, and when a trunk extending to a manual office is seized, a coder is seized also. This coder responds to the digits in the desired number 80 and sends out the corresponding coded impulses upon the response of the operator as is the practice in handling calls from machine switching automatic offices to manual 85 call indicator offices.

Referring now to the drawings comprising Figs. 1-10, inclusive, they can be understood best if Figs. 1, 2, and 5 are laid out in order with the corresponding lines at the ends thereof in alignment; with Figs. 90 3 and 4 arranged under Fig. 2 with the corresponding interconnecting lines at the edges thereof in alignment; and with Fig. 6 similarly placed under Fig. 5. When thus arranged, the drawings show by means of 95 the usual circuit diagrams, a sufficient amount of apparatus in a system embodying the principles of the invention to allow the invention to be understood thoroughly, when considered in connection with the accompanying description.

Referring now particularly to Fig. 1, there is shown an automatic substation A, whose line terminates in the step by step automatic office in the line switch C, which 100 line switch has access to a number of first selectors, such as E, through the medium of an equal number of trunk circuits, such as 105

the trunk circuit TC. Associated with each trunk circuit such as TC there is a secondary switch, such as SS, which has access to a number of directors, such as the one shown in the dotted enclosure in the upper right-hand corner of Fig. 1.

The first selectors such as E have access on any level to a number of second selectors such as F. The second selector F has access on one level to trunks to a manual office by way of repeaters such as the repeater R, Fig. 2.

Associated with each repeater such as R, there is a secondary switch such as the secondary switch SS'. These secondary switches have common access to a number of coders, such as the coder shown in Figs. 3 and 4.

Each of the trunks extending from the automatic office to the call indicator manual office such as the one comprising conductors 130 and 131, terminates at the manual office in a single plug cord circuit, such as the cord circuit O.

In the manual office there is a registering device such as the one shown in Fig. 6 at each operator's position. This device responds to the coded impulses which are sent in upon the depression of an assignment key, such as K, by the operator when she sees the line lamp, such as L, lighted at the associated cord circuit. When the coded impulses have all come in, the correct combination of lamps in the lamp bank, Fig. 6 is lighted, whereupon the operator plugs up the number into the multiple, at the same time releasing her assignment key.

The line switch C, Fig. 1, in which the line of substation A terminates is of the usual rotary type, in which the wipers have no normal position and move in a forward direction only. The secondary switches SS, SS', and the sender S, Figs. 1, 2, and 4, respectively, are mechanically identical with the line switch C.

The automatic selectors such as E are mechanically of the well-known vertical and rotary type and, accordingly, have one hundred sets of bank contacts arranged in horizontal rows or levels.

The master digit control switch MDC, Fig. 3, is of the so-called "minor switch" type. The wipers of this switch are moved in one plane only by the operating magnet 226, and are restored to normal by release magnet 227 under the joint control of off normal contacts 228 and armature 209 and its resting contact of release relay 201. Each of the digit register switches DR-DR³, inclusive, is mechanically identical with the master digit control switch MDC, with the exception that the wipers of the digit registers are normally standing off the bank, while the wipers of the master digit control switch MDC are normally in engagement

with the first set of bank contacts. The station register SR is similar to any one of the digit registers.

The director, Fig. 1, may be similar to the one shown in the co-pending application of Nelson, Serial No. 573,175, filed July 6, 1922.

In order to enable the invention to be more clearly understood, a detailed description of the method of handling a call will now be given. For this purpose, it will be assumed that the subscriber at substation A desires to call a subscriber whose line terminates in the manual call indicator office, the subscriber at substation A' for example. It will be assumed further that the manual call indicator office is listed in the directory as 39, or the numerical equivalent thereof, and that the number assigned to the line of substation A is 2590, and that the station designation is W. Consequently, the number to be dialled is 39-2390-W.

When the receiver is removed at substation A, a circuit is closed over line conductors 2 and 4 for line relay 6 of the line switch C. Line relay 6, upon energizing, places ground on private normal conductor 3, at armature 11, thereby making the calling line busy and closing a circuit for switching relay 5 and stepping magnet 12 in series. Also, relay 5 at armature 10 connects test wiper 14 to the junction of switching relay 5 and stepping magnet 12. In case the trunk upon which the wipers of the line switch are standing is idle, the operation of armature 10 does not produce any effect and switching relay 5 energizes immediately. Assuming the trunk to be busy, however, switching relay 5 is short circuited by the ground potential encountered on the test contact of the trunk by test wiper 14 and does not energize. In this case, the wipers 13-15, inclusive, are advanced step by step in search of an idle trunk by the buzzer-like action of stepping magnet 12, which operates from ground picked up by test wiper 14.

When an idle trunk is reached, which trunk it will be assumed is the one comprising conductors 19-21, inclusive, and terminating in bank contacts 16-18, inclusive, switching relay 5, being no longer short circuited, energizes in series with stepping magnet 12. Stepping magnet 12, however, does not energize at this time on account of the high resistance of switching relay 5. Upon energizing, switching relay 5 opens the test circuit and prepares the holding circuit at armature 8, and at armatures 7 and 9 disconnects line conductors 2 and 4 from line relay 6 and ground and extends them by way of wipers 13 and 15, bank contacts 16 and 18, conductors 19 and 21, and armatures 34 and 36 to the windings of line relay 31 of the trunk circuit TC. Line relay 31, upon energizing, closes a circuit for re-

lay 50 of the secondary switch SS at armature 38. Relay 50, upon energizing, places ground on release trunk conductor 20 and disconnects said release trunk conductor 20 from release trunk conductor 43 at armature 53; closes a circuit for switching relay 51 and stepping magnet 52 in series at armature 55; and at armature 54 connects test wiper 61 to the junction of switching relay 51 and stepping magnet 52.

The secondary switch SS now selects an idle trunk in the same manner as described for the line switch C, which trunk it will be assumed is the one comprising conductors 68-71, inclusive, and terminating in bank contacts 64-67, inclusive. Switching relay 51, upon energizing, when the idle trunk is selected, opens the test circuit and grounds release trunk conductor 69 at armature 57; grounds the discriminating conductor 68 at armature 56; connects up the operating conductor 70 at armature 58; and at armature 59 connects up the outgoing sending conductor 71. Release relay 72 and discriminating relay 73 of the director to which the seized trunk extends, energize and perform the usual functions upon the above named seizure. In response to the connecting up of the outgoing sending conductor, repeating relay 32 in the trunk circuit TC energizes and places a bridge across conductors 42 and 44 of the selector E at armature 41, whereupon line relay 80 of the selector E energizes and closes a circuit for release relay 81 at armature 90. Release relay 81, upon energizing, prepares a circuit for vertical magnet 49 at armature 92, and at armature 91 places ground on release trunk conductor 43.

In response to the connecting up of the operating conductor 70 of the director trunk, the trunk tone is sent back through the working contact of armature 58 and said armature, and through the small condenser 40 in the trunk circuit TC to the lower heavy talking conductor, as is disclosed in the Nelson application above referred to, to inform the calling subscriber that he may begin to dial the various digits in the desired number. When the subscriber operates his calling device in accordance with the first digit 3 in the number of the desired office, the circuit of line relay 31 of the trunk circuit TC is opened a corresponding number of times at the calling substation. Upon each deenergization of line relay 31, an impulse of current is transmitted at armature 39 over the operating conductor 70 to the operating circuit of the director, whereupon the director operates in the usual manner to record the digit. Each of the following digits is transmitted to the director in the same manner.

When the two office digits have been received by the director, the sending portion

thereof is rendered operative, whereupon sending relay 74 interrupts the circuit of repeating relay 32 at armature 76 in accordance with the digits necessary to trunk the call to the desired office.

Each time repeating relay 32 is deenergized in response to one of the interruptions produced in its circuit in accordance with the first office digit, it opens the circuit of line relay 80 at armature 41. Upon each of the deenergizations of line relay 80 thereby produced, an impulse of current is delivered to vertical magnet 49 by way of armature 92 and its working contact and series relay 82. By the operation of vertical magnet 49, the wipers 100-102, inclusive, are raised opposite the desired level of bank contacts. Slow acting series relay 82 is maintained energized in series with vertical magnet 49 throughout the vertical movement, and closes at armature 93 a circuit for stepping relay 83 in series with off normal contacts 89, which contacts close upon the first vertical step of the switch. Upon energizing, stepping relay 83 closes a locking circuit for itself at armature 94, and at armature 95 prepares a circuit for rotary magnet 86.

Series relay 82 deenergizes upon the termination of the vertical movement and closes a circuit for rotary magnet 86 at armature 93. Rotary magnet 86, upon energizing, advances the wipers 100-102, inclusive, into engagement with the first set of bank contacts in the level opposite which they are raised and, near the end of its stroke, opens the circuit of stepping relay 83 at interrupter contacts 88. Stepping relay 83, upon deenergizing, opens the circuit of rotary magnet 86 at armature 95. Rotary magnet 86, upon deenergizing, closes its interrupter contacts 88 again.

If the trunk terminating in the first set of bank contacts is idle, switching relay 84 energizes immediately. However, if the trunk is busy, switching relay 84 is short circuited by the ground potential which is present on the test contact thereof, and stepping relay 83, upon energizing from this same source of ground potential, closes a circuit for rotary magnet 86 again at armature 95, whereupon the wipers are advanced into engagement with the next set of bank contacts. This alternate operation of stepping relay 83 and rotary magnet 86 continues until an idle trunk is reached, which trunk it will be assumed is the one terminating in bank contacts 103-105, inclusive, and extending to the second selector E. When said idle trunk is reached, switching relay 84, being no longer short circuited, energizes in series with stepping relay 83. Stepping relay 83, however, does not energize at this time on account of the high resistance of switching relay 84. Switching relay 84, upon energizing, removes ground from armature 105.

ture 90 of line relay 80 at armature 98, thereby opening the circuit of release relay 81; opens the test circuit and prepares the holding circuit at armature 97; and at armatures 96 and 99 disconnects conductors 42 and 44 from the windings of relay 80 and extends them by way of wipers 100 and 102 and bank contacts 103 and 105 to the line relay of the selector F. The line and release relays (not shown) of the selector F now energize and the latter places ground on the associated release trunk conductor, thereby establishing the usual holding circuit for switching relay 84 through bank contact 104, test wiper 101, and armature 97 and its working contact before slow acting release relay 81 has had time to deenergize.

When the second digit in the office number is sent out by the director, the line relay 20 of the selector F is controlled at armature 41 of repeating relay 32 to step the wipers of the selector F up to the desired level of bank contacts, whereupon the trunk hunting operation takes place in the usual manner. It will be assumed that the trunk comprising conductors 110-112, inclusive, and extending to the manual exchange by way of the repeater R is the one seized by the selector F.

Upon the seizure of the associated trunk, line relay 114 of the repeater R energizes over conductors 110 and 112 and closes a circuit for release relay 115 at armature 121. Release relay 115, upon energizing, places ground on release trunk conductor 111 at armature 123, closes a circuit for the lower or polarizing winding of electro-polarized relay 113 at armature 124, and at armature 122 closes a circuit for line relay 135 of the secondary switch SS' by way of armature 128 and its resting contact and the normally closed contacts controlled by armature 142. Line relay 135, upon energizing, closes a circuit for switching relay 136 and stepping magnet 137 in series at armature 138, and at armature 139 connects test wiper 147 to the junction of switching relay 136 and stepping magnet 137. The secondary switch SS' now selects an idle trunk in the usual manner, the trunk comprising conductors 153-156, inclusive, for example. Switching relay 136, upon energizing when the idle trunk is selected, opens the test circuit and grounds release trunk conductor 155 at armature 143; connects up operating conductor 156 at armature 144; connects up the outgoing impulse conductors 153 and 154 to trunk conductors 130 and 131 at armatures 140 and 141; and at armature 142 closes a locking circuit for itself and opens the circuit of line relay 135. Line relay 135 now deenergizes, but does not produce any result at this time.

In the coder, release relay 201, Fig. 3, energizes in response to ground being placed

on the conductor 155 by the secondary switch SS', as pointed out above. Upon energizing, relay 201 disconnects ground at one point from the common conductor 163 at armature 207; and at armature 209 disconnects ground from release conductor 224 and places ground on wiper 230 of the master digit control switch MDC. The coder is now ready to receive the digits in the subscriber's number.

When the director, Fig. 1, sends out the first digit 2 in the subscriber's number, the circuit of line relay 114 of the repeater R is interrupted twice. Upon deenergizing in response to each of the two interruptions produced in its circuit, line relay 114 places ground on the operating conductor 156 at armature 120 by way of the working contact of armature 144 and said armature, wiper 148, and bank contact 152. The effect of this is to send two impulses of current to the operating magnet 221 of the digit register DR, Fig. 3, the circuit being as previously traced to operating conductor 156, and thence by way of series relay 202, wiper 229 of the master digit control switch MDC, the first associated bank contact, and operating magnet 221 of the digit register DR to battery. By the operation of magnet 221, the wipers 231 and 232 of the digit register DR are advanced into engagement with the second set of associated bank contacts. Relay 202 is energized in series with magnet 221, and, being slow acting, retains its armature attracted throughout the series of impulses. Upon energizing, relay 202 closes a circuit for slow acting relay 203. Relay 203, upon energizing, prepares a circuit for operating magnet 226 of the master digit control switch MDC at armature 211. 10

At the end of the series of impulses, relay 202 deenergizes and opens the circuit of relay 203 at armature 210. Relay 203, however, being slow acting, retains its armature attracted for an interval. As a further result of the deenergization of relay 202, it completes the circuit of operating magnet 226 at armature 210 by way of the working contact of armature 211 and said armature, and the resting contact of armature 217 and said armature. Magnet 226 now energizes and advances the wipers 229 and 230 of the master digit control switch MDC into engagement with the second set of bank contacts. Relay 203, upon deenergizing, opens the circuit of magnet 226 at armature 211. 110

When the next digit 3 is sent out by the director, the wipers of the second digit register DR' are advanced into engagement with the third set of bank contacts by the three impulses of current transmitted over the operating conductor through wipers 229 and the second associated bank contact. At the end of the series of impulses wipers 229 120

and 230 of the switch MDC are advanced into engagement with the third set of bank contacts in the hereinbefore described manner.

- 5 Similarly, the wipers of the third digit register DR² are advanced into engagement with the ninth set of bank contacts in response to the sending out of the third digit 9 in the subscriber's number by the director, 10 after which the wipers of the master digit control switch MDC are advanced into engagement with the fourth set of bank contacts in the manner described above.

When the fourth digit 0 in the subscriber's number is transmitted by the director, the ten impulses sent over the operating conductor by the line relay of the repeater R cause the wipers of the fourth digit register DR³ to be advanced into engagement 20 with the tenth set of bank contacts, after which the wipers of the master digit control switch MDC are advanced into engagement with the fifth set of bank contacts.

When the director sends out the station digit W, which digit is numerically equivalent to the digit 9, nine impulses of current are transmitted to the operating magnet of the station register SR in the usual manner. Consequently, the wipers of the station register SR are advanced into engagement with the ninth set of bank contacts, after which the wipers of the switch MDC are advanced into engagement with the sixth set of bank contacts in the above described manner.

- 35 In the director, Fig. 1, switching relay 75 energizes after the last digit has been sent out and places ground on conductor 70 at armature 79, whereupon switching relay 30 in the trunk circuit TC energizes over a circuit which includes conductor 70, bank contact 66, wiper 62, working contact of armature 58 and said armature, and armature 39, and its working contact. Upon energizing, relay 30 locks itself to release trunk conductor 20 at armature 35; disconnects line relay 31 at armatures 34 and 36; unites conductors 19 and 21 with conductors 42 and 44, respectively, at armatures 33 and 37; and at the normally closed contacts controlled by armatures 33 and 37 disconnects the local bridge controlled by repeating relay 32 from across conductors 42 and 44, leaving the line relay of the repeater R, to which the connection has been extended, under the direct control 55 of the calling loop. Line relay 31 of the trunk circuit TC, upon deenergizing in response to being disconnected by relay 30, opens the circuit of slow acting relay 50 of the secondary switch SS at armature 38, whereupon relay 50 deenergizes; unites the conductors 20 and 42 and removes the local ground connection from conductor 20 at armature 53; and at armature 55 opens the circuit of relay 51, whereupon relay 51 deenergizes and disconnects its wipers. The di-

rector now reverts to common use and is restored to normal in the usual manner.

Returning now to the coder, wiper 230 of the switch MDC, Fig. 3, upon coming into engagement with the sixth associated bank contact as above described, closes a circuit for the upper winding of relay 205 by way of the resting contact of armature 220 and said armature. Relay 205, upon energizing, closes a locking circuit for its lower winding 75 over the outgoing impulse conductors 153 and 154 at armatures 216 and 216', and at armature 215 closes a circuit for relay 206. Relay 206, upon energizing, closes a point in the circuit for placing ground on start conductor 241 at armature 218; disconnects magnet 226 at armature 217; closes a locking circuit for itself at armature 219, and at armature 220 opens the initial circuit of relay 205, leaving relay 205 energized by means 85 of its lower winding.

In the manual office line relay 302 of the cord circuit O, Fig. 5, energizes over conductors 130 and 131 in response to the lower winding of relay 205, Fig. 3, being bridged 90 across conductors 153 and 154, as described above, conductors 153 and 154 being connected to conductors 130 and 131 through the secondary switch SS and the repeater R, as pointed out hereinbefore. Line relay 302, 95 upon energizing, closes a circuit for the lamp L at armature 306, the circuit including the resting contact of armature 317 and said armature.

The operator, upon noting the lighted condition of the lamp L depresses the assignment key K individual to the trunk, thereby grounding the locking conductor 311 of her call indicator set and closing a circuit for relay 301. Relay 301, upon energizing, disconnects conductors 130 and 131 from the windings of the repeating coil and extends them to relays 325-327, inclusive, by way of conductors 309 and 310. Incidentally, line relay 302 deenergizes and the lamp L becomes extinguished.

In the automatic office relay 205 of the coder, Fig. 3, deenergizes in response to the circuit change produced by relay 301, Fig. 5, as described above; disconnects itself from conductors 153 and 154 at armatures 216 and 216'; and at armature 215 places ground on start conductor 241 by way of the working contact of armature 218 and said armature.

When ground is placed on the start conductor 241, start relay 249, Fig. 4, energizes; disconnects wipers 269 and 270 of the sender from stepping magnet 250 at armatures 264 and 265 and connects them to the lower winding of relay 247 and the winding of relay 248, respectively; disconnects ground from certain contacts in the bank of wiper 269 at armature 266; and at armature 266' connects sending relay 245 to the intermittently grounded conductor associated with the 130

constantly operating interrupter 271. The wipers of the sender S now make a complete revolution under the control of sending relay 245, and control the sending out 5 by sending relay 245 of the heavy and light negative impulses and the light positive impulses in accordance with the number set up on the registers, Fig. 3.

In the following description, the impulses 10 which are transmitted from battery over conductor 153 and trunk conductor 130 to the manual office and back over trunk conductor 131 and conductor 154 to ground are termed negative impulses, and such impulses 15 as are sent in the reverse direction over the above named conductors to the manual office and back to ground are termed positive impulses. All positive impulses are sent through the high resistance 263, 20 Fig. 4, which is the reason they are called light positive impulses. Certain of the negative impulses are sent through resistance 263 and, consequently, are called light negative impulses. The remainder of the negative impulses are sent from battery direct 25 and do not pass through resistance 263. Consequently they are called heavy negative impulses.

Returning now to the detailed description, 30 relay 245, upon its first effective energization after it is connected up at armature 266 as pointed out above, connects up conductors 153 and 154 at armatures 251 and 252. This, however, does not produce any 35 result at this time for the reason that none of the impulse preparing relays 246-248, inclusive are energized. As a further result of the above mentioned energization of relay 245, it closes a circuit for stepping magnet 250 of the sender S at armature 253. Stepping magnet 250, upon energizing, advances 40 the pawl of its armature into engagement with the next notch of the wiper driving ratchet wheel, but does not move any of the 45 sender wipers.

Upon the subsequent deenergization of relay 245, conductors 153 and 154 are disconnected at armatures 251 and 252, and the circuit of stepping magnet 250 is opened 50 at armature 253. Upon the deenergization of stepping magnet 250 wipers 267-270, inclusive, of the sender are advanced in a counterclockwise direction into engagement with the first set of associated bank contacts. 55

Wiper 268, upon coming into engagement with the first associated bank contact, closes a circuit for the upper winding of relay 247 as follows: from ground by way of the 60 right-hand wiper of the station register SR, the ninth associated conductor, first contact in the bank of wiper 268 and said wiper, and the upper winding of relay 247 to battery. Relay 65 247, upon energizing, opens a point in the

circuit of relay 248 at armature 260, and at armatures 257 and 258 prepares the circuit for sending out the light positive impulse of the station digit W.

Upon the next energization of sending 70 relay 245 in response to the closing of its circuit at interrupter 271, it closes the usual circuit for stepping magnet 250 of the sender S at armature 253 with the result above described. As a further result of the energization of relay 245, it sends out at armatures 75 251 and 252 the light positive impulse for which the circuit is prepared. The circuit over which this impulse is transmitted to the manual office is as follows: from ground 80 conductor by way of resistance 263, working contact of armature 257 and said armature, working contact of armature 251 and said armature, conductor 154, previously traced circuit to the lower or positive trunk 85 conductor 131, armature 303, Fig. 5, and its working contact, conductor 310, relays 327, 326, and 325 in series, conductor 309, working contact of armature 304 and said armature, trunk conductor 130, previously traced 90 circuit to and through conductor 153, armature 252, Fig. 4, and its working contact, armature 255 and its resting contact, and armature 258 and its working contact, to ground. 95

When relay 245 deenergizes, the light positive impulse is terminated at armatures 251 and 252, and the circuit of stepping magnet 250 is opened at armature 253, whereupon the wipers of the sender are advanced into engagement with the second set of bank contacts in response to the deenergization of stepping magnet 250. With the wipers of the sender in engagement with the second set of bank contacts, relay 246 100 105 energizes over the following circuit: from ground by way of the right-hand wiper of the station register SR, the ninth associated bank contact, the associated conductor, the second contact in the bank of wiper 267 and 110 said wiper, and relay 246 to battery. Relay 246, upon energizing, prepares the circuit at armatures 254 and 255 for sending out the heavy negative impulse in the station digit W. 115

Consequently, sending relay 245, upon energizing the next time, in addition to closing a circuit for stepping magnet 250, sends out a heavy negative impulse over the following circuit: from grounded battery by 120 way of the working contact of armature 255 and said armature, working contact of armature 252 and said armature, in the reverse direction over the previously traced circuit to armature 251, armature 251 and its working contact, and the working contact of armature 254 to ground. 125

Upon the next deenergization of relay 245, the heavy negative impulse is terminated and the wipers of the sender are 130

advanced into engagement with the third set of bank contacts, whereupon relay 248 energizes and prepares a circuit for sending out the light negative impulse of the station digit W, the circuit of relay 248 being as follows: from ground by way of the third contact in the bank of wiper 270 and said wiper, armature 265 and its working contact, armature 256 and its resting contact, resting contact of armature 260 and said armature, and relay 248 to battery.

Upon the succeeding energization of relay 245, the light negative impulse is sent out over the following circuit: from grounded battery by way of resistance 263, working contact of armature 262 and said armature, resting contact of armature 255 and said armature, working contact of armature 252 and said armature, previously traced circuit to armature 251, armature 251 and its working contact, and armature 261 and its working contact to ground.

Upon the following deenergization of relay 245, the light negative impulse is terminated at armatures 251 and 252, and magnet 250 advances the wipers of the sender into engagement with the fourth set of bank contacts. With the wipers of the sender in engagement with the fourth set of bank contacts, relay 246 energizes and prepares the circuit at armatures 254 and 255 for sending out the heavy negative impulse in the first digit 2 of the subscriber's number. The circuit of relay 246 is as follows: from ground by way of right-hand wiper 232 of the digit register DR, the second associated bank contact, the associated conductor, the fourth contact in the bank of wiper 267 of the sender S and said wiper, and relay 246 to battery.

When relay 245 energizes again, the heavy negative impulse is sent out in the previously described manner.

Upon the subsequent deenergization of relay 245, the heavy negative impulse is terminated and the wipers of the sender are advanced into engagement with the fifth set of bank contacts. With the wipers of the sender S in engagement with the fifth set of bank contacts, none of the impulsive circuit preparing relays 246-248, inclusive, are energized and no impulse is sent when relay 245 energizes.

Upon the following deenergization of relay 245, the wipers of the sender S are advanced into engagement with the sixth set of bank contacts, whereupon relay 248 energizes through the sixth contact in the bank of wiper 270 and said wiper, and thence over the previously traced circuit and prepares the impulsive circuit for sending out the light negative impulse of the digit 2 at armatures 261 and 262.

Upon the next energization of relay 245 the light negative impulse is sent out at

armatures 251 and 252, as hereinbefore described.

Upon the following deenergization of relay 245, the wipers of the sender are advanced into engagement with the seventh set of bank contacts, whereupon relay 247 energizes over the following circuit: from ground by way of the right-hand wiper of the digit register DR', the third associated bank contact, the associated conductor, the seventh contact in the bank of wiper 268 and said wiper, and the upper winding of relay 247 to battery. Relay 247, upon energizing, prevents the energization of relay 248 at armature 260, and at armatures 257 and 258 prepares the impulsive circuit for sending out the light positive impulse of the second digit 3 in the subscriber's number. Consequently, the light positive impulse is sent out upon the following energization of the sending relay 245.

When the wipers of the sender are advanced into engagement with the eighth set of bank contacts upon the following deenergization of relay 245, relay 246 energizes over the following circuit: from ground by way of the right-hand wiper of the digit register DR', the third associated bank contact, the associated conductor, eighth contact in the bank of the wiper 267 and said wiper, and relay 246 to battery. Relay 246, upon energizing, prepares the impulsive circuit for the sending out of the heavy negative impulse of the second digit 3 in the subscriber's number. Consequently, the heavy negative impulse is sent out upon the next energization of relay 245.

Upon the following deenergization of relay 245, the wipers of the sender S are advanced into engagement with the ninth set of bank contacts, whereupon relay 248 energizes through the ninth contact in the bank of wiper 270 and said wiper and prepares the impulsive circuit for sending out the light negative impulse of the second digit 3 in the subscriber's number. Consequently, the light negative impulse is sent out upon the following energization of the sending relay 245.

Upon the next deenergization of relay 245, the wipers of the sender are advanced into engagement with the tenth set of bank contacts, whereupon relay 248 energizes through the tenth contact in the bank of wiper 270 and said wiper, and the light negative impulse of the third digit 9 in the subscriber's number is sent out upon the next energization of the sending relay 245.

Upon the next deenergization of relay 245, the wipers of the sender S are advanced into engagement with the eleventh set of bank contacts, whereupon relay 247 energizes over the following circuit: from ground by way of the right-hand wiper of the third digit register DR², the ninth con-

tact in the bank thereof, the associated conductor, the eleventh contact in the bank of wiper 268 and said wiper, and the upper winding of relay 247 to battery. Relay 247, 5 upon energizing, prepares the impulsing circuit for sending out the light positive impulse of the third digit 9 in the subscriber's number, and the light positive impulse is sent out upon the following energization of 10 sending relay 245.

When the wipers of the sender S are advanced into engagement with the twelfth set of bank contacts upon the following de-energization of sending relay 245, relay 246 15 is energized over the following circuit: from the ground by way of the left hand wiper of the third digit register DR², the ninth contact in the bank thereof, the associated conductor, the twelfth contact in the bank of wiper 267 20 and said wiper, and relay 246 to battery. Relay 246, upon energizing, prepares the impulsing circuit for sending out the heavy negative impulse of the third digit 9 in the subscriber's number, and the heavy negative 25 impulse is sent out upon the next energization of the sending relay 245.

When the wipers of the sender are advanced into engagement with the thirteenth set of bank contacts upon the next deenergization of sending relay 245, relay 248 energizes through the thirteenth contact in the bank of wiper 270 and said wiper, and prepares the impulsing circuit for sending out a light negative impulse. Consequently, the 30 first light negative impulse in the fourth digit 0 in the subscriber's number is sent out upon the next energization of the sending relay 245.

When the wipers of the sender S are advanced into engagement with the fourteenth set of bank contacts upon the next deenergization of sending relay 245, none of the 40 impulsing circuit preparing relays 246-248, inclusive, are energized, the wipers of the digit register DR² being in engagement with the tenth set of bank contacts. Consequently, no impulse is sent out upon the following 45 energization of sending relay 245.

When the wipers of the sender S are advanced into engagement with the fifteenth set of bank contacts upon the following de-energization of sending relay 245, relay 248 energizes through the fifteenth contact in the bank of wiper 270 and said wiper, and 50 prepares the impulsing circuit for sending out a light negative impulse. Consequently, the second light negative impulse of the fourth digit 0 in the subscriber's number is sent out upon the next energization of sending relay 245.

When the wipers of the sender S are advanced into engagement with the sixteenth set of bank contacts, upon the following de-energization of sending relay 245, wipers 55 267 and 268 encounter grounded contacts,

whereupon relay 246 energizes through wiper 267 and relay 247 energizes through its upper winding and wiper 268. Wiper 270 also is in engagement with a grounded contact, and since relays 246 and 247 are 70 energized, a circuit is closed for switching relay 116 of the repeater R as follows:

from ground by way of the sixteenth contact in the bank of wiper 270 and said wiper, armature 265 and its working contact, armature 256 and its working contact, armature 259 and its working contact, operating conductor 156, contact 152 in the bank of the secondary switch SS', Fig. 2, wiper 148, armature 144 and its working contact, armature 120 of line relay 114 and its working contact, and switching relay 116 to battery. Switching relay 116, upon energizing, opens the circuit of switching relay 136 of the secondary switch SS' and closes a locking circuit 80 for itself at armature 128, disconnects the tone condenser 126 at armature 127, and at armatures 125 and 129 disconnects conductors 130 and 131 from the impulsing circuit extending to the coder and connects them to a closed bridge which includes the upper winding of electro-polarized relay 113 and impedance 117. This operation also places conductors 130 and 131 in talking relation to conductors 110 and 112 through the heavy 85 talking condensers of the repeater R. It will be understood that the operation of switching relay 116 occurs soon enough to disconnect conductors 130 and 131 from the impulsing circuit before the next energization 90 of sending relay 245, Fig. 4.

Switching relay 136 of the secondary switch SS', upon deenergizing in response to the opening of its circuit by switching relay 116 of the repeater R, as pointed out above, disconnects its wipers at armatures 140-144, inclusive, thereby removing ground from release trunk conductor 155. When this occurs, release relay 201, Fig. 3, deenergizes and opens the circuit of relay 206 at 105 armature 209. Relay 206, upon deenergizing, removes ground from start conductor 241 at armature 218, whereupon relay 249, Fig. 4, deenergizes; disconnects sending relay 245 at armature 266'; places ground at 110 armature 266 on the contacts in the bank of wiper 269, corresponding to the ungrounded contacts in the bank of wiper 270; and at armatures 264 and 265 connects wipers 269 115 and 270 to stepping magnet 250 through the local interrupter contacts of said stepping magnet 250. When this occurs, the wipers of the sender S are spun to normal position by the buzzer-like action of stepping magnet 250, which magnet buzzes only as long 120 as either wiper 269 or wiper 270 is in engagement with a grounded contact.

As a further result of the deenergization of release relay 201, Fig. 3, it places ground 125 on release conductor 224 at armature 209, 130

whereupon the wipers of the switch MDC, digit registers DR-DR², inclusive, and the station register SR are restored to normal through the action of their respective release magnets, the digit register DR, for example, being restored to normal by release magnet 222. The circuit of release magnet 222 is opened at off normal contacts 223 when the wipers of the digit register DR.

10 reach normal position. The circuits of the other release magnets are opened in like manner. The coder is now at normal and is ready to handle another call.

Referring now particularly to Fig. 6, the effect of the transmission of the various series of impulses as described above will now be taken up and described. Positive relay 326, upon energizing in response to the light positive impulse in the station digit W, which impulse does not operate negative relay 325 on account of the way the latter is poled nor relay 327 on account of its marginal adjustment, closes at armature 329 a circuit for the first station set up relay 401 as follows: from ground by way of the lower pair of contacts on the assignment key K, Fig. 5, locking conductor 311, working contact of armature 329 and said armature, armature 338 and its resting contact, armature 354 and its resting contact, and the right-hand winding of relay 401 to battery. Relay 401, upon energizing, locks itself through its left hand winding at its inner armature, and at its outer armature closes a point in the circuit of the lamp W.

When the impulse subsides, relay 326 de-energizes and opens the initial circuit of relay 401, leaving said relay 401 locked up through its left hand winding.

40 When the heavy negative impulse of the station digit W comes in, negative relay 325 and marginal relay 327 are energized. Upon energizing, marginal relay 327 closes a circuit for the right hand winding of the second station set up relay 402 as follows: from ground by way of conductor 311, working contact of armature 330 and said armature, armature 335 and its resting contact, armature 351 and its resting contact, and the right hand winding of relay 402 to battery. Relay 402, upon energizing, closes a locking circuit for its left hand winding at its inner armature, and at its second armature, counting from the left, closes still another point in the circuit of the lamp W.

Negative relay 325, upon energizing in response to the above mentioned heavy negative impulse in the station digit W, closes at armature 328 a circuit for relay 332 in series with the left hand winding of the marginally adjusted relay 331. Relay 332 energizes at this time but relay 331 does not energize on account of its marginal adjustment. Upon energizing, relay 332 closes a locking circuit for itself in series with the

right hand winding of relay 331 at armature 336. No current flows through this locking circuit at this time, however, owing to the fact that the initial circuit of relay 332 is still established. As a further result of the energization of relay 332 it disconnects armature 329 of positive relay 326 from the first operating conductor and connects it to the third operating conductor at armature 338, and closes at armature 337 a circuit for relay 340 by way of armature 349 and its resting contact. Relay 340, upon energizing, shifts the first operating conductor at armature 354 and at armature 352 closes a locking circuit for itself in series with relay 339. Relay 339 does not energize at this time owing to the fact that it is short circuited by the ground potential which is applied to both of its terminals.

When relays 325 and 327 deenergize at the end of the heavy negative impulse, relay 325 opens the initial circuit of relay 332, whereupon the locking circuit of relay 332 becomes effective and relay 331 energizes. Upon energizing, relay 331 disconnects armature 328 from the left hand terminal of relay 332 and connects it to the right hand terminal at armature 333; places a shunt around armature 337 and its working contact at armature 334; and at armature 335 disconnects armature 330 of relay 327 from the second operating conductor and connects it to the fourth.

When the light negative impulse of the station digit W comes in relay 325 is energized again, and short circuits relay 332 and the right hand winding of relay 331 at armature 328, whereupon relay 332 deenergizes, but relay 331 remains energized.

When the light negative impulse subsides, relay 325 deenergizes and opens the circuit of relay 331, whereupon relay 331 also deenergizes. Upon deenergizing, relay 331 opens the initial circuit of relay 340 at armature 334, whereupon relay 339 energizes in series with relay 340 through armature 352 and its working contact. Upon energizing, relay 339 shifts the circuits which it controls at armatures 349-351, inclusive, to the corresponding armatures of relays 341.

In a similar manner the thousands, hundreds, tens, and units relays are operated. It is thought that it is sufficient to point out that the set up relay in each set, of which the reference numeral ends with 1 is operated in case the positive relay 326 is energized at the beginning of a series of impulses; the relay of which the reference numeral ends with 2 is operated by marginal relay 327 in case the first negative impulse of the series is heavy; the relay of which the reference numeral ends with 3 is operated by the positive relay 326 in case the corresponding series of impulses contains a positive impulse between the two negative impulses; and the relay the reference numeral of which ends

with 4 is operated by marginal relay 327 in case the second negative impulse of the corresponding series is heavy.

In this case, since the numerical part of 5 the subscriber's number is 2390, the second relay 412 in the thousands group is operated; the first and second relays 421 and 422 of the hundredths group are operated, the 10 third and fourth relays 433 and 434 in the tens group are operated, and one of the units relays are operated.

When relay 347 energizes in response to 15 the termination of the last impulse in the units digit 0, it places ground on conductor 380 at armature 376, whereupon the called number is displayed on the operator's indicator lamps.

After the operator has noted the number 20 set up, she releases the assignment key K, thereby removing ground from conductor 311, whereupon the various energized relays controlled by conductor 311 deenergize and the lighted indicator lamps become extinguished. As a further result of the restoration 25 of the key K the circuit of relay 301 is opened. Relay 301, upon deenergizing, disconnects conductors 130 and 131 from conductors 309 and 310 at armatures 304 and 305 and extends them again to 30 the windings of line relay 302, whereupon the line relay 302 again energizes and lights the lamp L. The circuit of line relay 302 at this time includes impedance 117 and the upper winding of electro-polarized relay 113 of 35 the repeater R. Relay 113, however, is not energized at this time on account of the fact that the current flow in each winding is in such a direction as to tend to neutralize the effect of the current flow in the other winding.

The operator now tests the called line in the usual manner by tapping the tip of her plug P against the sleeve of the jack J, and, assuming the line to be idle, she inserts the 40 said plug into the said jack. When this occurs, sleeve relay 313 of the cord circuit O and the cut-off relay of the called line energize in series, the latter relay performing the well known function of clearing the line 45 of its attachments. Sleeve relay 313, upon energizing, extinguishes the lamp L at armature 317, and disconnects the operator's head set from the tip of the plug P and connects up the tip and ring conductors of the 50 cord circuit to armatures 314 and 315 of ring cut off relay 312, respectively. The operator now throws the proper one of the four ringing keys K'-K⁴, inclusive, the key K, for example, whereupon ringing current of 55 the proper frequency to ring the bell at substation A' is projected out over the called line.

When the called subscriber responds to 60 the ringing of his bell by removing his receiver, a direct current bridge is closed

across the conductors of the called line, whereupon ring cut off relay 312 energizes through its upper winding; removes the shunt from around its lower winding at armature 319, so as to maintain the said relay energized independent of its upper winding; and at armatures 314 and 315 disconnects the tip and ring conductors of the cord circuit from its own upper winding and the source of ringing current and extends them through the right-hand windings of the repeating coil to the windings of back-bridge relay 303. Back-bridge relay 303, upon energizing, reverses the current flow in conductors 130 and 131 at armatures 307 and 308. When this occurs, the electro-polarized relay 113 in the repeater R energizes and reverses the current flow in conductors 110 and 112 at armatures 118 and 119. This reversal has no particular function in the present case but is used in other cases for various purposes, such as, for example, to operate a subscriber's meter when a subscriber is calling who has a meter individual to his line either at 90 the substation or at the central office. The two subscribers may now converse with each other as desired, the talking circuits being outlined by the heavy conductors, and when they have finished they replace their receivers.

When the receiver is replaced at substation A' back bridge relay 303 in the cord circuit O deenergizes and reverses the current flow in conductors 130 and 131 to normal, whereupon relay 113 in the repeater R deenergizes and reverses the current flow in conductors 110 and 112 to normal.

When the receiver is replaced at the calling substation A, the circuit of relay 114 of 105 the repeater R is opened. Relay 114, upon deenergizing, opens the circuit of slow acting release relay 115 at armature 124. Release relay 115, upon deenergizing, opens the circuit of the lower winding of electropolarized relay 113 at armature 124; opens the circuit of relay 116 at armature 122, whereupon the relay 116 deenergizes; and at armature 123 removes ground from release trunk conductor 111, whereupon the selectors 115 E and F are restored to normal position in the usual manner, the selector E, for example, being restored to normal by release magnet 85 upon the closure of its circuit by armature 98 of switching relay 84. The circuit of release magnet 85 is opened at the off normal contacts 87 by the switch shaft when the latter reaches normal position. As a further result of the removal of the ground potential from the release trunk conductor 111, switching relays 5 and 30 of the line switch C and the trunk circuit TC, respectively, deenergize, thus restoring conditions 125 in the associated circuits to normal.

As a result of the deenergization of relay 130

110 of the repeater R, the bridge is removed from across conductors 130 and 131 leading to the manual office, whereupon line relay 202 in the cord circuit O deenergizes and 5 closes at armature 306 a circuit for the lamp L by way of the working contact of armature 317 and said armature. When the operator notes the lighted condition of the lamp L she removes the plug P from the 10 jack J, whereupon the associated relays de-energize, and the lamp L becomes extinguished.

Assuming that the subscriber at substation A makes another call and that he is calling a subscriber in a manual office in which there are no party lines, and consequently no party line designation, the director in use, governed by the office digits of the number as is disclosed in the Nelson application hereinbefore referred to, sends out the digit 1 after the call has been trunked to the desired manual office and the four digits of the subscriber's number have been sent to the coder in use. Assuming that the coder used is the one shown in Figs. 3 and 4, which coder, it will be understood, is accessible to secondary switches such as the secondary switch SS', Fig. 2, associated with trunks leading to straight line manual offices as well as to secondary switches associated with trunks leading to party line manual offices, the digit 1 has the effect of stepping the wipers of the station register SR, Fig. 3, into engagement with the first set of bank contacts, and of advancing the master digit control switch MDC into switching position. Since the first set of bank contacts of the station register SR are dead, the two light negative impulses for which the sender is normally set 40 are sent out ahead of the subscriber's number. This has the effect of connecting up the operating circuits to the thousands set of relays in the straight line call indicator in use, the station's set of indicator lamps being omitted in the straight line call indicators. Otherwise the call indicators, for the sake of uniformity, are made the same for both the straight line and the party line offices.

50 Referring now to Figs. 2 and 3, the method of giving a calling subscriber a busy tone in case no coder is available when he calls will be explained. The individual test contact 159 in the set of overflow contacts 55 157-160, inclusive, in the bank of the secondary switch SS', Fig. 2, of which there is only one set provided for each switch, is normally grounded by relay 164 as are the similar contacts in the banks of each of the other coder selecting secondary switches. This, of course, makes the set of contacts test busy and ordinarily none of the secondary switches stop on the set of overflow contacts. However, assuming that all the coders become busy, ground is removed from

conductor 163 at all points corresponding to armature 207 of relay 201, Fig. 3, whereupon relay 164 is no longer short circuited and energizes in series with resistance 165, thereby removing the ground potential from all 70 the test contacts such as test contact 159. Then, assuming the secondary switch SS' to be hunting for a coder at this time its wipers are rotated past the contacts in which the trunks extending to the busy coders terminate and are stopped in engagement with the overflow contacts 157-160, inclusive. When switching relay 136 energizes at this time, as it does in the hereinbefore described manner, it connects up wiper 148 at armature 144, whereupon busy signalling current is applied to the upper talking conductor over a circuit which extends as follows: from 75 grounded battery by way of the left hand winding of the busy tone transformer, the 80 associated condenser, bank contact 160, wiper 148, armature 144 and its working contact, condenser 126, and armature 127 and its resting contact to the upper heavy talking conductor. This busy tone informs the calling subscriber that he cannot obtain the desired connection for the time being. Upon 85 hearing this busy tone the calling subscriber replaces his receiver, whereupon the partly established connection is released in the 90 usual manner.

I claim:

1. In a telephone system, a set of register switches for registering the digits in a telephone number, a set of relays for transmitting impulses in accordance with a non-decimal code, and means including a rotary switch for controlling said relays in accordance with the setting of said register switches.

2. In a telephone system, a set of register switches for registering the digits in a telephone number, a set of relays for transmitting impulses in accordance with a non-decimal code, means including a rotary switch for controlling said relays in accordance with the setting of said register switches, a visual indicator for indicating telephone numbers to an operator, and a decoder responsive to the impulses constituting a code for displaying the corresponding telephone number on said indicator.

3. In a code transmitter, a plurality of circuit preparing relays, means for causing a plurality of different settings of said relays, means including a circuit closing relay for closing the circuits prepared by said circuit preparing relays, and means for energizing the circuit closing relay after each setting of the circuit preparing relays.

4. In a code transmitter, a group of circuit preparing relays, a plurality of registers, means for energizing said preparing relays in permutations according to the setting of each of said registers in turn, means

105

100

95

115

110

120

125

130

including a circuit closing relay for closing the circuits prepared by said circuit preparing relays, and means for energizing said circuit closing relay after each energization of the circuit preparing relays.

5. The combination, with a metallic circuit, of means for transmitting heavy and light impulses over said circuit, the light impulses being of either polarity, said 10 means comprising permutational relays for preparing the circuit, a circuit closing relay for closing the circuit each time after it is prepared, and means for energizing said relays a plurality of times to transmit a code 15 representing the digits in a telephone number.

6. The combination, with a metallic circuit, of means for transmitting heavy and light impulses over said circuit, the light 20 impulses being of either polarity, said means comprising permutational relays for preparing the circuit, a circuit closing relay for closing the circuit each time after it is prepared, and means including a rotary step 25 by step switch for energizing said relays.

7. In a multi-office telephone system, a step by step automatic office, a manual office, an operator's switchboard in said manual office, trunk lines leading from said automatic office to said manual office and terminating thereat in said switchboard, a plurality of coders in said automatic office comprising registering and transmitting means, means responsive to a seizure of one of said 30 trunk lines in said automatic office for connecting such trunk line to an idle one of said coders, means for operating the registering means of such coder in accordance with the number of the desired manual line, 35 means effective thereupon for signalling the operator at the switchboard in the manual office, and means controlled by the response of the operator at such switchboard for operating the sending means of the coder in 40 use to transmit coded impulses over the said seized trunk line to indicate to the operator 45 the desired number.

8. In a multi-office telephone system, a step by step automatic office, a manual office, an operator's switchboard in said manual office, trunk lines leading from said automatic office to said manual office and terminating thereat in said switchboard, a plurality of coders in said automatic office comprising registering and transmitting 50 apparatus, means responsive to the impulses representing the part of a called number indicative of said manual office for operating switching mechanism in said automatic office to seize one of said trunk lines, means responsive to such seizure for connecting the seized trunk line to an idle one of said coders, means for operating the registering means of each coder in accordance with impulses representing the portion of the called number indicative of the desired manual line, means effective thereupon for signalling the operator at the said switchboard, means controlled by the response of the operator for operating the sending means of the coder in use to transmit code impulses over the said seized trunk line to indicate to the operator the desired number.

9. The combination of a step-by-step device for transmitting impulses of different characters on succeeding steps of the step-by-step device, of a circuit through which the impulses are transmitted, and a relay energized momentarily upon each step of the device to close said circuit.

10. The combination in a step-by-step device for transmitting impulses of different characters on succeeding steps of the step-by-step device, of a circuit through which the impulses are transmitted, a relay energized momentarily upon each step of the device to close said circuit, and means including contacts on said relay for controlling the step-by-step movement of said device.

In witness whereof, I hereunto subscribe my name this 13th day of October, A. D., 1922.

JOHN E. OSTLINE.
